UNITED STATES PATENT OFFICE

HORACE M. WOOLLEY, JR., OF CLEVELAND, OHIO

SHORE

Application filed January 12, 1928. Serial No. 246,154.

This invention relates to a shore and more particularly to an adjustable shore.

It has particular utility as a support for the forms used in concrete building construction, although its utility extends to any use requiring a temporary support. In concrete building construction it is necessary to support the forms or molds for the concrete floors and other parts of the building during its 10 erection by props or shores founded upon the adjacent sub-structure. Ordinarily, these supports comprise wooden props cut to suitable length and perhaps shimmed up by wedge members.

15 An object of the invention is to provide an adjustable shore which may be extended through a wide range of different lengths.

Another object is to provide a shore which may be accurately adjusted and is of a rigid 20 construction and relatively few number of parts.

Another object is to provide an adjustable shore that is easily manipulated and adjusted and is positively held in its adjusted positions.

25 Other objects and advantages will become apparent as the description proceeds.

An embodiment of the invention is shown in the accompanying drawings, wherein—

30 Fig. 1 is a side elevation of the shore;

Fig. 2 is a horizontal section taken on line 2—2 of Fig. 1;

Fig. 3 is a fragmentary side elevation of the shore taken adjacent the upper end of 35 the fixed member;

Fig. 4 is a horizontal sectional view taken on the line 4—4 of Fig. 1;

Fig. 5 is a side elevation of the jack assembly of the shore; the lower shoe of the movable member, the jack nut and a part of the jack screw being shown in section;

Fig. 6 is an end elevation of the jack assembly, the stud of the movable member being broken away to show the upper end of 45 the jack screw; and

Fig. 7 is a horizontal sectional view taken on line 7—7 of Fig. 1.

The shore comprises a fixed and a movable member telescopically arranged, and indicated, generally, in Fig. 1 of the drawing, as

1 and 2, respectively. The fixed member includes an upwardly extending part 3 preferably in the form of a steel pipe. A foot plate 4 is welded or otherwise secured to the bottom of this pipe and forms the foot or 55 base of the shore. This foot plate may be provided with openings or recesses through which suitable securing means may be passed to hold the same in fixed position upon its mounting. The pipe is provided throughout 60 the greater portion of its length with spaced openings 5, the purpose of which will subsequently become apparent, while the upper end thereof is conically tapered.

The movable member is preferably formed 65 of a pair of spaced parallel vertically extending side elements 6 which may be simply studs of suitable dimensions. Extending across the upper ends of the elements 6 is a head block 7 secured to the elements by means of U- 70 shaped straps 8. The lower end of the elements seat in and are connected together by a rectangular shoe 9. This shoe is formed with a bottom portion 10 and upwardly extending flanges 11 around its entire periphery.

The center of the bottom portion 10 is provided with an opening, the purpose of which will later be explained. The bottom portion also has downwardly extending bosses 12 adjacent to the central opening therein, the 75 number of which may vary although two are shown in the drawing. These bosses are pro-

vided with tapped bores into which are threaded headed bolts 13 which are adapted to retain an annular washer member 14 between the head thereof and the lower end of the bosses 12. Each flange 11 of the shoe is pro-

vided with a suitable number of openings through which screws or other securing means 80 15 may pass to secure the side elements to the shoe. Intermediate the head block 7 and the shoe 9 the movable member is provided with braces 16 extending between and secured to the side elements 6. These braces are prefer-

ably in the form of inverted channeled stampings, the arms 17 of which extend across and are connected to the outer sides of the side elements while the web portion 18 of the stamping is bent up at its opposite ends to 85

190 15 may pass to secure the side elements to the shoe. Intermediate the head block 7 and the shoe 9 the movable member is provided with braces 16 extending between and secured to the side elements 6. These braces are prefer-

ably in the form of inverted channeled stampings, the arms 17 of which extend across and are connected to the outer sides of the side elements while the web portion 18 of the stamping is bent up at its opposite ends to 100

form vertically extending flanges 19. The flanges 19 bear against the inner sides of the side elements and are connected thereto by suitable screws or other means 20. An opening 21 is formed centrally of the part 18 of the stamping and is adapted to guide the rigid member of the shore during the relative movement of the two members.

The means for moving the movable member 10 on the fixed member may be called generally the jack assembly of the shore. This means comprises the sleeve 22 externally threaded at 23 adapted to slidably fit on the pipe 3 and having an outwardly extending lug 24 adjacent its lower end. The lug 24, as well as the main body of the sleeve, are each provided with horizontally aligned openings 25 and 26, while the sleeve has another opening 26^a in horizontal axial alignment with opening 26. 15 A U-shaped pin 27, one arm of which is shorter than the other, is slidably fitted within these openings. The longer arm of the pin is provided with a rivet or other retaining member 28 at its end to prevent complete withdrawal of the pin through the opening 25. The shorter arm of the pin is adapted to extend through various of the openings 5 in the fixed member when such openings have been aligned with the openings 26 and 26^a of the 20 sleeve. In this way the sleeve may be adjustably secured on the fixed member and an initial approximate adjustment of the shore obtained. If desirable the pin 27 may be provided with a notched portion 29 adapted to engage with the lug 24 so as to prevent the pin being jarred loose while the shore is in adjusted position. An internally threaded nut 30 is rotatably mounted on the sleeve. This nut 30 has an annular flange 31 at its 25 upper end which is retained between the washers 14 and the bottom 10 of the shoe 9. In this way the nut is free to rotate on the sleeve while at the same time it will impart rectilinear movement to the shoe and hence to the movable member. The nut is provided with an operating handle 32 which may be either integral therewith or otherwise connected thereto.

In operation, the shoe is placed in the position 30 in which it is to be used and the foot 4 is secured to the base. The approximate adjustment of the shore to the height required is effected by withdrawal of the pin 27 and the movement of the sleeve 22 to the desired position, whereupon the pin 27 is again inserted through the aligned openings in the sleeve and pipe 3. When in this position the head block 7 should be almost or lightly in engagement with the underside of the form which the shore is to support. Then the nut 30 is rotated by the handle 32, in the proper direction to move upwardly on the sleeve 22. This movement of the nut, because of its engagement with the underside of the shoe 11, forces

the movable member 2 of the shore upwardly until the head block is tightly engaged beneath the underside of the form to be supported. Of course, the removal of the shore is effected in the reverse manner, the nut 30 being rotated so as to have downward movement on the sleeve which results in the flange 31 bearing against the washer 14 and causing the movable member 2 to descend both because of the pulling action exerted thereby and because of gravity. As the member 2 descends the pipe 3 will pass through the openings 21 in the various braces 16, and the upper conical end of the pipe facilitates this passage. It will thus be seen from the foregoing description that the shore is formed of a relatively few number of parts, is of strong construction, rigidly braced and permits of a first and approximate adjustment, and then a final and accurate adjustment.

Although the embodiment of the invention illustrated is a preferred one the invention should not be understood as limited thereto, since it is susceptible of many variations and adaptations within the scope of the appended claims.

Having thus described my invention, what I claim is:

1. A shore comprising a movable member, a fixed member having a series of spaced openings therethrough, a threaded sleeve arranged on said fixed member and having an outwardly extending lug at its lower end, said sleeve and said lug each having horizontally aligned openings therethrough, a pin 95 slidably arranged in said openings and adapted to be selectively engaged in the spaced openings in the fixed member so as to adjustably position the sleeve thereon, and a nut on said sleeve adapted when rotated 100 to move said movable member.

2. A shore comprising a fixed member and a movable member telescopically arranged, an externally threaded sleeve on said fixed member, an internally threaded nut on said sleeve, said movable member being provided with a shoe at its lower end having downwardly extending bosses on its underside and means carried by said bosses and cooperating with the nut so as to allow the latter to rotate and to operatively move the movable member.

3. A shore comprising a fixed and a movable member, said movable member having side elements extending on opposite sides of the fixed member, braces connecting the side elements at spaced intervals throughout their length and guiding the movable member in its movement on the fixed member, a shoe connecting the lower ends of the side elements and surrounding the fixed member, a sleeve mounted on the fixed member and extending through said shoe, and a nut arranged on said sleeve and rotatably connected with said

shoe whereby rotation of the nut will raise or lower the movable member.

4. A shore comprising a fixed and a movable member, the fixed member being provided with spaced openings therethrough, the movable member having side elements extending on opposite sides of the fixed member, braces connecting the side elements at spaced intervals throughout their length and guiding the movable member in its movement on the fixed member, a shoe connecting the lower ends of the side elements and surrounding the fixed member, a threaded sleeve mounted on the fixed member and carrying a pin in its lower end adapted to be selectively inserted in any one of the spaced openings in the fixed member, a nut arranged on said threaded sleeve and having an annular flange at its upper end adapted to bear against the underside of said shoe, and said shoe having means engaging beneath said annular flange whereby when the nut is rotated the movable member will be raised or lowered.

5. A shore comprising a fixed member and a movable member telescopically arranged, a sleeve on said fixed member having adjustable connection with said movable member, said sleeve and said fixed members having openings arranged to be brought into registration, a lug on said sleeve having an opening therethrough, a pin having an arm adapted to extend through the aligned openings for locking said sleeve to said fixed member and a second arm slideable in the opening of said lug, and means for preventing complete separation between said second arm and said lug.

In testimony whereof, I hereunto affix my signature.
